UNITED STATES PATENT OFFICE.

SILAS WITHERELL, OF FORT MADISON, IOWA, ASSIGNOR TO LOUIS C. HINZE,
OF SAME PLACE.

HOUSE-DOOR LETTER-BOX.

SPECIFICATION forming part of Letters Patent No. 472,007, dated March 29, 1892.

Application filed May 1, 1891. Serial No. 391,201. (No model.)

To all whom it may concern:

Be it known that I, SILAS WITHERELL, a citizen of the United States, residing at Fort Madison, in the county of Lee and State of Iowa, have invented certain new and useful improvements in House Letter-Boxes; and I do hereby declare that the following is a full, clear, and exact description of the same, reference being had to the annexed drawings, making a part of this specification, and to the letters of reference marked thereon.

This invention relates to certain new and useful improvements in house letter-boxes; and it has for its objects, among others, to provide a letter-box of this character which shall be cheap and neat in appearance, which shall protect the contents against rain, snow, and dust, simple in its manner of operation, provided with an attachment for the reception of papers and packages too large to be placed in the box, which shall disclose the presence of mail-matter without being opened, which shall mar the door but little, and which can be readily applied to a door in such a manner as to furnish reasonable security against removal of the letters or of the box by malitiously-inclined persons.

Other objects and advantages of the invention will hereinafter appear, and the novel features thereof will be specifically defined by the appended claims.

The invention is clearly illustrated in the accompanying drawings, which, with the letters of reference marked thereon, form a part of this specification, and in which—

Figure 1 is a perspective view of my improved house letter-box, shown applied to a door with the lid and movable receptacle shown open. Fig. 2 is a central vertical cross-section through the same, with the said parts closed.

Like letters of reference indicate like parts in both of the views.

Referring now to the details of the drawings by letter, A designates a portion of a door or any other suitable support to which the box is to be affixed.

The box B is formed of any suitable material and of the required size, being preferably rectangular in shape, as shown, and it is

provided with a fixed bottom and a hinged top C. This top is pivoted upon the rod D, which is secured at its ends in the ears b of the side walls of the box, as shown, the lid or cover having a surrounding depending flange 55 c, which embraces the upper end of the box to make a water-tight joint, the side walls of the box being cut away at the rear to form a space d, in which the rear portion of this flange works, as seen best in Fig. 2, so as to 60 allow the cover to fly open when released into the position in which it is shown in Fig. 1. A spring E is arranged around the pivot-rod within the box with one end acting upon the inner face of the cover, as shown in Fig. 1, 65 and the other end bearing against the inwardly and forwardly inclined ledge F, as seen in the same figure, the said ledge being provided to prevent removal of the contents of the box, an oppositely-inclined ledge G being provided for a like purpose, as seen best in Fig. 2, the mail being designed to be introduced through the opening e between these ledges, as seen in Fig. 2.

A suitable spring-catch H is provided with 75 in the box for the purpose of holding the cover closed, the said catch being actuated to release the cover by means of a push-button I, at the front of the box, acting upon the said catch, as seen in Fig. 2.

In the front wall of the box I provide a transparent opening f, through which it may be readily discerned whether or not there is any mail in the box.

J are lugs cast upon the front wall of the 85 box and designed to receive and hold between them a door-plate or other desired analogous device.

At the bottom of the front wall of the box I provide a means for holding newspapers 90 and the like. It consists of a piece of wire K, having its ends secured to the box in any suitable manner, and formed near the said connection with coils g, the wire being bent at its center and curved between its bend and 95 the connection with the box, as shown, so that it will readily yield to the insertion of packages and yet firmly hold them in place.

The box is provided with a side opening i, 100 in which is fitted the movable portion of the

box. The box is affixed in position on the door by means of screws or other analogous means *j*, as seen in Fig. 1, which are passed through the rear wall of the box and into the door or other support, so that they are concealed from view, and the manner of securing the box in place is thus hidden from view, whereby the box cannot be removed from the door by maliciously-inclined persons.

10 L is the movable part of the box. It is pivoted at its lower outer corner on a suitable pivot-pin *k*, held in the side walls of the box proper, as shown in Fig. 1. The bottom of this movable portion may form the bottom 15 of the box, or the box may have a fixed bottom in addition thereto, as above described. The sides of this movable portion or door are at an angle to its front wall, as seen in Fig. 1, and the front wall is provided with a suitable 20 knob or handle *l*, by which it may be opened and closed. It is designed to set in flush with the coincident portions of the box proper. This movable portion of the box is provided at its inner lower end with an inclined 25 plate or partial bottom M, which serves to throw the mail outward when the movable portion is opened.

The operation will be readily understood from the foregoing description when taken 30 in connection with the annexed drawings, and a detailed description thereof is not deemed necessary.

The box can be used either for collection or delivery.

In order to lock the movable portion from the inside of the house, I provide a pin N, movable in the door and adapted to engage a hole *m* in the side of the movable portion, as seen in both views. When this pin is pushed in, it locks the movable portion. When pulled 40 out sufficiently to disengage the said hole, the movable portion is free to be opened.

What I claim as new is—

1. A house letter-box consisting of the box proper having spring-actuated pivoted cover 45 with flange and the side walls of the box cut away at the rear to form a space for the working of the said flange, and a forwardly-inclined ledge and a rearwardly-inclined ledge at the top of the front of the box, as set forth. 50

2. A house letter-box consisting of the box proper having spring-actuated pivoted cover with front and rear flanges and the side walls of the box cut away at the rear to form a space for the working of the rear flange, a 55 forwardly-inclined ledge and a rearwardly-inclined ledge at the top of the box, and a movable part L, having sides and front and pivoted at the lower outer corner and having at its inner lower end an inclined plate, substantially as and for the purpose specified.

In testimony that I claim the above I have hereunto subscribed my name in the presence of two witnesses.

SILAS WITHERELL.
